UNITED STATES PATENT OFFICE.

MARIE STEINER, OF MILWAUKEE, WISCONSIN.

DESIGN FOR AN UNDERGARMENT-REINFORCE.

SPECIFICATION forming part of Design No. 27,583, dated August 31, 1897.

Application filed April 29, 1897. Serial No. 634,481. Term of patent 14 years.

To all whom it may concern:

Be it known that I, MARIE STEINER, a citizen of the United States, residing at Milwaukee, in the county of Milwaukee and State of Wisconsin, have invented and produced a new and original Design for an Undergarment-Reinforce; and I do hereby declare the following to be a full, clear, and exact description of the same, reference being had to the accompanying drawing, forming a part thereof.

The said drawing is a perspective view illustrating the peculiar configuration of my undergarment-reinforce, and, as shown in said drawing, the leading or material feature of my design comprises a central portion of a generally oval shape, from one end of which there extends a square-ended single tongue having straight parallel sides, while from the opposite end of said central portion there extend two similar square-ended and straight-sided parallel tongues. The single tongue terminates in a straight end and has sides parallel with each other for the greater portion of its length, beginning with the end, and then the sides of said tongue are formed in concave rounded lines merging into the convex rounded lines of the described oval

central portion. The two parallel tongues projecting from the opposite end of the described oval central portion have similar straight ends, and the outer side of each of said tongues is straight for the greater portion of its length, beginning with the end, and then follows a concave rounded line merging into the convex rounded line of the said oval central portion, while the adjacent inner side lines of each of the said two parallel tongues are straight their entire length. The described oval central portion is rounded up at the center to a plane above that of its side edges, as indicated by the lines of shading extending from side to side of said central part in the drawing.

Having thus described my invention, what I claim as new, and desire to secure by Letters Patent, is—

The design for an undergarment-reinforce substantially as herein shown and described.

In testimony whereof I affix my signature in presence of two witnesses.

MARIE STEINER.
